UNITED STATES PATENT OFFICE.

WILLIAM E. NICKERSON, OF CAMBRIDGE, MASSACHUSETTS, ASSIGNEE TO GILLETTE SAFETY RAZOR COMPANY, OF BOSTON, MASSACHUSETTS, A CORPORATION OF DELAWARE.

REINFORCED BLADE.

Application filed January 9, 1919. Serial No. 270,347.

To all whom it may concern:

Be it known that I, WILLIAM E. NICKERSON, a citizen of the United States, residing at Cambridge, in the county of Middlesex and State of Massachusetts, have invented certain new and useful Improvements in Reinforced Blades, of which the following is a specification.

My invention relates to blades in which the cutting portion is provided with a sheet-metal backing or reinforcement, and is particularly applicable to single-edged blades for safety razors. In such blades, as commonly constructed heretofore, the cutting portion has substantially the same width as the complete blade and the backing is folded around the rear edge of the cutting portion, which is firmly gripped and held by friction between the folds of the backing. The principal object of the present invention is to provide a blade of this general character in which a comparatively narrow strip of steel can be used as the cutting portion and securely held between the folds of a relatively wide backing, which adds to the cutting portion the width required for the complete blade. In this way a saving in cost can be effected, and a blade can be produced which will be rigid as a whole although its cutting portion is made from sheet steel of such thickness as to be readily flexible.

The object above referred to is accomplished in the manner hereinafter described in connection with the accompanying drawing, in which:

Figure 1 is a plan view showing one form of blade embodying my invention;

Figure 2 is a transverse section on the line 2—2 in Figure 1;

Figure 3 is a plan view of a blade of slightly modified construction;

Figure 4 is a transverse section on the line 4—4 in Figure 3;

Figure 5 is a plan view of the blank from which the backing shown in Figures 3 and 4 is made; and

Figures 6, 7 and 8 are plan views of blades embodying other modifications, the backing shown in Figure 8 being partly broken away.

In the blade shown in Figures 1 and 2 the cutting portion 2 is made of sheet steel of

any desired thickness and is provided with a cutting edge 3, and the backing 4 is made of a rectangular piece of sheet metal folded upon itself and provided on one side with a number of tongues 5 struck up from the sheet metal, in line with one another, and on the other side with a corresponding number of perforations 6. Each perforation 6 registers with the corresponding tongue 5 on the other side of the backing when the latter is folded, and is of such size that the tongue can be passed through it, the tongues being preferably formed with semi-circular free ends and the perforations being correspondingly shaped, as shown. The parts are assembled by folding the backing and bending over the tongues nearly to their final position, then inserting the rear edge of the cutting portion 2 between the folds of the backing until it brings up against the tongues, and then turning down the tongues tightly on the perforated fold of the backing as shown in Figure 2, whereby the cutting portion is firmly gripped between the folds. The tongues are so located with reference to the width of the cutting portion 2 that the completed blade has the desired width and the cutting edge 3 projects beyond the edges of the backing to the desired extent, and in addition to tying the parts together and serving as stops to position the cutting portion during the assembling of the parts the tongues also render it impossible for the cutting portion to slip backward within the backing when the blade is in use.

The blade shown in Figures 3 and 4 is like the one just described except that each fold of the backing 4' is provided with one or more tongues 5' and one or more perforations 6' arranged in alternation and each perforation is circular instead of semi-circular in form, so that when each tongue is bent around the rear edge of the cutting portion 2 its free end is received within the corresponding perforation as shown in Figure 4. I prefer this form of blade to that shown in Figures 1 and 2 because the free ends of the tongues are flush with the backing instead of over-lying it. The alternation of the tongues and perforations in the folds is not essential, but since the cutting

portion is gripped between the free end of each tongue and the fold from which the tongue is formed it is desirable to alternate the tongues and perforations in order to cause alternate tongues to engage opposite sides of the cutting portion and thereby tie the latter securely to both folds.

The modification shown in Figure 6 is particularly intended for blades which are to be used in holders having stops at the ends of the guard for engaging and positioning the cutting edge of the blade and in which the cutting portion of the blade is so thin as to be flexible. In this modification the backing 4" is provided at each corner with a projection 7 which extends toward the cutting edge of the blade and terminates a short distance behind the bevel of the edge, thereby supporting the cutting portion 2 at the ends of the latter where it engages the positioning stops above referred to, and where rigidity is specially important in order to prevent the cutting portion from bending when pressed against the stops. Otherwise the construction is as shown in Figures 3 and 4.

Instead of securing the cutting portion and the backing together by means of tongues passing around the rear edge of the cutting portion, this may be done in the manner illustrated in Figure 7, which shows a blade wherein the backing 4^a is provided at each end of one fold with a tongue 8 and the cutting portion 2 is held in place by bending these tongues around its ends and overlapping them upon the opposite fold of the backing. In this case a stop for positioning the cutting portion is preferably provided by means of additional tongues 9 formed from one of the folds of the backing and passing through perforations 10 in the other fold far enough to cross the rear edge of the cutting portion.

In the blade shown in Figure 8 the tongues 9 above described are rendered unnecessary by forming notches 11 in the ends of the cutting portion 2' and locating the tongues 8' in the notches 11 when folded over, these tongues being provided at the ends of the backing 4^b as in the construction shown in Figure 7.

It will be seen that in each form of blade above described the greater part of the width of the blade is provided by the backing and that although the cutting portion is located at a distance from the rear edge of the backing the folds of the latter cannot spring apart sufficiently to release the cutting portion because of the fact that the parts are tied together at points close to the cutting portion, so that a secure frictional grip on the latter is provided. My invention resides primarily in these general features and is applicable to a wide variety of blades, including blades in which the

cutting portion is forged instead of being stamped out of sheet steel.

I claim:

1. A reenforced blade comprising a folded backing and a cutting portion located in part between the folds of the backing and terminating at a distance from its folded edge, said backing being provided with tongues bent around the cutting portion at points close to the latter whereby said cutting portion and both of the overlying folds are secured together. 70

75 2. A reenforced blade comprising a folded backing and a flexible cutting portion located in part between the folds of the backing, each fold being provided at each end with a projection extending beyond its intermediate portion toward the exposed edge of the cutting portion and terminating closely adjacent to the latter, and means for clamping said cutting portion between the overlying folds of the backing in fixed relation thereto. 80

85 3. A reenforced blade comprising a folded backing and a cutting portion located in part between the folds of the backing and terminating at a distance from its folded edge, said backing being provided with tongues bent around the inner edge of the cutting portion whereby the latter is gripped between the folds. 90

95 4. A reenforced blade comprising a folded backing, a cutting portion located in part between the folds of the backing and terminating at a distance from its folded edge, and a plurality of tongues formed in part from one fold and in part from the other fold of the backing and each bent around the inner edge of the cutting portion, whereby the latter is gripped between said folds. 100

105 5. A reenforced blade comprising a folded backing and a cutting portion located in part between the folds of the backing and terminating at a distance from its folded edge, each fold being provided with one or more tongues bent around the inner edge of the cutting portion and turned down upon the latter within a perforation formed in the other fold. 110

115 6. A reenforced blade comprising a folded backing, a flexible cutting portion located in part between the folds of the backing and terminating at a distance from its folded edge, each fold being provided at each end with a projection extending toward and terminating closely adjacent to the exposed edge of the cutting portion, and a plurality of tongues formed from the backing and bent around the inner edge of the cutting portion whereby the latter is gripped between said folds. 120

125 7. A reenforced blade comprising a folded backing, a flexible cutting portion located in part between the folds of the backing and terminating at a distance from its 130

folded edge, each fold being provided at each end with a projection extending toward and terminating closely adjacent to the exposed edge of the cutting portion, and
5 a plurality of tongues formed in part from one fold and in part from the other fold of the backing and each bent around the

inner edge of the cutting portion and turned down upon the latter within a perforation formed in the overlying fold.

Signed at Boston, Mass., this 8th day of January, 1919.

WILLIAM E. NICKERSON.
